UNITED STATES PATENT OFFICE

CHARLES S. BATDORF, OF BROOKLYN, NEW YORK.

CHECK-CONTROLLED LIQUID-DISPENSING APPARATUS.

1,135,251.

Specification of Letters Patent. Patented Apr. 13, 1915.

Application filed December 4, 1913. Serial No. 804,560.

To all whom it may concern:

Be it known that I, CHARLES S. BATDORF, a citizen of the United States, and a resident of Brooklyn, in the county of Kings and State of New York, have invented certain new and useful Improvements in Check-Controlled Liquid-Dispensing Apparatus, of which the following is a specification.

The invention pertains more particularly to apparatus by means of which predetermined quantities of a liquid may be discharged from one container to another or from a reservoir owned by a dealer into a tank or other receptacle owned by a customer or purchaser, or into a tank or receptacle to be emptied into a tank or receptacle owned by a purchaser.

The invention is intended more particularly, though not exclusively, for the use of garages and dealers who supply, as a part of the business transacted, predetermined quantities of gasoline and oil to owners of automobiles, and one purpose of the invention is to provide suitable means whereby in the sale of gasoline or other liquid, both the dealer and purchaser may have a positive assurance that the predetermined quantity of the liquid purchased has been delivered, and also whereby in the sale and delivery of the gasoline or other liquid the dealer, having possibly a number of employees, may ascertain who sold the gasoline and also the quantity sold, to-wit, the number of gallons during, say, any predetermined interval.

At the present time the owner of garages and places where gasoline is supplied to owners of automobiles, have means for delivering predetermined quantities of gasoline to owners of automobiles, but these means are subject to the intelligence, will and faithfulness, as well as the carelessness, of employees, and it frequently happens that a person purchasing, say, three gallons of gasoline will not receive that quantity but sometimes, due to carelessness or other reason, either less than that quantity or more than that quantity.

My invention compels the accurate delivery of the predetermined quantity of liquid ordered, it being impossible to continue the apparatus of my invention in use except upon the delivery to a purchaser of the exact quantity of gasoline or the like ordered by him. Both the dealer and the purchaser may, therefore, always have the assurance of their business being transacted fairly, the

purchaser receiving no more and no less gasoline or the like than he ordered, and the dealer having the knowledge that the purchaser has received the quantity and only 60 the quantity of gasoline or the like purchased.

The invention will be fully understood from the detailed description hereinafter presented, reference being had to the accompanying drawings, in which:

Figure 1 is an end view, partly broken away and partly in section, of a machine embodying my invention; Fig. 2 is a front elevation, partly broken away and partly in 70 substantially central vertical section, of the same; Fig. 3 is a top view, partly broken away and partly in transverse section, of the same, and Fig. 4 is a view, partly broken away and partly in vertical section, illustrating the application of my invention to a container for delivering a predetermined quantity of gasoline or other liquid at each complete operation of a plunger therein, the apparatus shown, aside from the features of 75 my invention, being of known character and commonly used for delivering predetermined quantities of gasoline from one container to another.

In the drawings 10 designates the main 85 casing inclosing the novel operative features of my invention, 11 a shaft extending through said casing and having on one end a crank handle 12 for its manual operation, 13 a pinion wheel on the other end of said 90 shaft, 14 a vertical plunger rod or rack-bar engaged by said pinion wheel and operable vertically therefrom, 15 a plunger secured on the lower end of said rod or bar and having an upwardly opening valve of usual 95 character controlling a port therethrough, 16 a cylinder within which is formed a chamber of predetermined capacity as one gallon liquid measure, within which the plunger 15 has its movement and which is 100 provided at one end with inlet ports 17 for gasoline or the like, 18 a liquid discharge pipe leading from the top of the cylinder 16 for dispensing the liquid in predetermined charges to any container intended to 105 receive it, and 19 a container supporting the casing 10 and inclosing the cylinder 16 and adapted to contain the gasoline or other liquid in bulk to be dispensed in accurate quantities with the use of my invention, the 110 container 19, cylinder 16, plunger 15, and discharge pipe 18 being of known character.

The casing 10 has flat sides, a rectangular lower portion, and a semi-circular upper portion formed by a semi-circular plate 20 hinged at one edge, at 21, to the main body 5 of the casing. At the front of the lower portion of the casing 10 is provided a removable door 22 equipped with a suitable lock 23 and at its lower edge having studs 24 to enter recesses formed in the bottom of the casing 10. The door 22 will be removed 10 when it is desired to remove the tokens from the chamber 25 formed within the lower portion of the casing 10, and said door may be of any convenient form and construction 15 and secured in any convenient manner. When the door 22 is in position closing the lower front portion of the casing 10, its upper edge overlaps the front lower edge of the semi-circular top 20 and locks said 20 top in its closed position.

The upper end of the casing 10 is provided with an entrance 26 for disks or the like constituting keys, checks or tokens, one of which is shown and numbered 27, by 25 which the apparatus may be operated, and in the absence of which the apparatus is rendered inoperative. The casing 10 may be of any suitable outline and through it extends the shaft 11 which is commonly employed 30 in connection with the container 19 for operating the plunger-rod 14. One side of the casing 10 is plain and flat and contains no features on its exterior of any special moment, and the other side of the 35 casing 10 is formed of the plate 28 and a disk 29, said disk being provided with the crank handle 12 and free to be rotated on the shaft 11 or on a sleeve 30 which may be provided on said shaft in the event that the shaft, as originally constructed, requires to have a larger diameter in order to properly receive the casing 10. The disk 29 on its periphery is recessed, as shown in Figs. 1 and 2 to receive the surrounding portions of the plate 28, a shoulder 31 being formed, on the disk to match the edge 32 of the opening in the plate 28 which receives said disk. The disk 29 is held upon the shaft 11 or on the sleeve 30, as the case may be, by means of a collar 33 fitting on the end of said shaft and fastened thereto in any suitable way, as by means of a screw or pin 34.

Within the casing 10 is provided a rotary frame 35 which has an outer drum-like portion 36 and an inner externally threaded sleeve 37, the latter fitting closely on the sleeve 30 and receiving an internally threaded frame 38 to be hereinafter referred to and which during the operation of the machine has a traveling movement imparted to it toward and from the part 36 of the frame 35. During the rotation of the sleeve 37, the frame 38 has no rotary movement but only a traveling movement back and forth on the sleeve 37, said frame 38

being held against rotary movement by means of a pin 39 which extends through a recess 40 in said frame.

The frame 35 is a hollow casting in the form of a drum or wheel and at one point 70 in its periphery is formed with a slot 41 adapted to register with the slot 26, said slot being formed between the facing sides of the walls 42, 43 and having a curved or chute-like lower end 44 extending downwardly and inwardly from the main portion of the slot to direct the keys or checks therefrom when the same are released to descend against said portion 44. One side of the slot 41 is entirely open, so far as the frame 35 is concerned, but there at is provided a pivoted arm 45 by which, during proper periods, the key or check 27 is held within the slot 41. At the side of the slot 41 opposite to the arm 45 and slightly above the upper end of the curved discharge chute 44, the disk 29 is formed with a shoulder 46 to coöperate with the arm 45 in supporting the key or check in the upper portion of the slot 41, said shoulder 46, however, being of such slight proportions as to allow the key or check 27 to at once descend through the slot 41 after the arm 45 has been relieved from it. Those portions of the frame 35 at the opposite sides of the slot 41 and which I designate as walls 42, 43, are preferably of substantial thickness, as shown by the dotted lines in Figs. 1 and 3, and have formed in them a through slot 46 which is on the arc of a circle, the slot being continued through the part 42 to the slot 41 and then from the slot 41 through the part 43, and this slot 46 is in line with the normal location for the key or check 27 when the machine is in operation and also 90 in line with an arm 47 which is integral with the disk 29 and projects inwardly therefrom. The arm 47 is slightly less in length and thickness than the like dimensions of the slot 46 and may, when the disk 29 is rotated without a key or check 27 being therein, freely pass through said slot. In the initial position of the parts of the machine preparatory to receiving through the entrance opening 26 a key or check 27, the arm 47 will stand within that portion of the slot 46 within the wall 42 of the frame 35, in which position it is shown in Figs. 1 and 3, and then when a key or check 27 is introduced through the opening 26 to the slot 41 of the frame 35 and is arrested at the position shown in Fig. 2, the arm 47 on the rotation of the disk 29 by means of the crank 12, will be carried against said key or check and through the latter compel the frame 35 to rotate, said key or check 27 at such time barring the entrance of the arm 47 to that portion of the slot 46 within the wall 43. The key or check 27 thus co-operates with the arm 47 as the medium; in 105 110 115 120 125 130

the operation of the machine, for connecting the disk 29 with the frame 35. After the frame 35 and disk 29 have rotated together during the requisite period, the key or check 5 46 will be released, in the manner herein-
after described, from the slot 41 and de-
scending through the same will be directed
into a chute 48 extending laterally over
the shaft 11 and then downwardly to the
10 chamber 25 within which the keys, checks
or other tokens may be collected and from
which they may be removed from time to
time as the owner of the machine may de-
sire. The frame 35 is fastened to the shaft
15 11 by means of a screw or pin 9 or otherwise,
and the disk 29 is normally free on said
shaft but rotates therewith when the arm
47 is against a key or check 27 held in the
frame 35, and also during the reverse ro-
20 tation of the disk 29, after the predeter-
mined quantity of gasoline has been de-
livered and the key or check 27 has been
released and descended to the chute 48.
During the rotation of the disk 29 in one
25 direction the arm 47 engaging the key or
check 27 connects said disk and frame 35,
and at this time a pawl 49 connected with
the frame 35 rides along with, without spe-
cially or necessarily at all acting against,
30 a ratchet tooth 50 formed on a ring 51 fas-
tened to said disk 29, and during the ro-
tation of the disk 29 in the reverse direction,
after the key or check 27 has left the slot 41,
the ratchet tooth 50 connected with said
35 disk will press against the end of the pawl
or dog 49 and through the same and there-
by cause the frame 35 to rotate with said
disk and become restored to its initial po-
sition with the slot 41 directly below the en-
40 trance slot 26 in the main casing.

It may be mentioned here as a part of the operation of the machine that when the frame 35 is in its initial position preparatory to receiving the key or check 27, the plunger 15 in the cylinder 16 will be at the bottom of said cylinder, and that said cylinder above the plunger will contain a predetermined quantity of liquid, such as gasoline, and that after the key or check 27 has been introduced to the frame 35 the disk 29 will through the handle 12, be rotated to carry the arm 47 against the key or check 27 and effect the rotation of the frame 35 and thereby the shaft 11 and through said shaft and intermediate parts cause the plunger 15 to ascend and discharge such predetermined quantity of gasoline or the like through the discharge pipe 18, this discharge being effected by the upward movement of the plunger 15 to the upper end of the cylinder 16. Upon the discharge of the predetermined quantity of gasoline or other liquid, the frame 35 will have made a complete rotation, ordinarily, and by the means hereinafter explained, the key or check 27

will have been released and descended to the chute 48. In the construction presented the plunger 15 will, at this time, however, be at the upper end of the cylinder 16, and must be returned to the lower end of said cylinder in order that the liquid may flow above the plunger for the next sale or delivery, and to accomplish this result the disk 29 is rotated in a reverse direction so that the shaft 11 may, through the pinion 13 and rod 14, cause the plunger 15 to descend within the cylinder 16. Since at this time the key or check 27 is not within the frame 35 and since the disk 29 is not directly connected with the shaft 11, I provide the ratchet tooth 50 on the ring 51 fastened to the disk 29 so that it, acting against the pawl 49, may rotate the frame 35 and through said frame the shaft 11. The arm 47 connected with the disk 29 coöperating with the key or check 27 serves to rotate the frame 35 in one direction, and the ratchet tooth 50 in connection with the pawl or dog 49, serves to communicate the reverse rotation of the disk 29 to the frame 35 and through said frame to the shaft 11 for effecting the descent to its initial normal position of the plunger 15 in the cylinder 16. During the rotation of the disk 29 and frame 35 to effect the discharge through the pipe 18 of a predetermined quantity of gasoline or the like, the pawl or dog 49 performs no duty but simply travels with the ratchet tooth 50. When the disk 29 and frame 35 are in rotation with the key or check 27 in position in said frame, a complete rotation of the frame is compelled from the fact that the key or check projects slightly outwardly beyond the periphery of the frame 35, as shown in Fig. 2, and that on the inner wall of the main casing 10 is secured a series of spring dogs 8 which incline laterally and at their lower ends are within a groove 52 formed in said frame 35 and extending entirely around the periphery thereof. During the rotation of the shaft 11, disk 29 and frame 35 to discharge a predetermined quantity of gasoline or the like, the spring dogs 8 perform no special function and being yielding permit the key or check 27 to ride below them, but on any attempt to reverse the rotation of the disk 29 and frame 35 before the full quantity of gasoline has been discharged from the cylinder 16, the projecting edge of the key or check 27 will be carried against the end of one of the spring dogs 8 and thereby said disk and frame will be arrested in their attempted reverse rotation. After the disk 29 and frame 35 have made a complete rotation in the proper direction to discharge the full quantity of gasoline from the cylinder 16, the key or check 27 will have returned to its initial position and by the means presently to be described, permitted to descend to the

outlet chute 48 and thereupon, there being no key or check in the frame 35, said frame by means of the handle 12, disk 29, tooth 50 and dog 49, may be readily reversed in motion to perform a complete rotation and effect the movement of the plunger 15 to the bottom of the cylinder 16.

The means for holding the key or check 27 within the slot 41 comprise, as hereinbefore described, the pivoted arm 45 and shoulder 46. The arm 45 is secured by a screw or pivot 53 upon a lug extending laterally from the inner edge of the frame 35, as clearly represented in Figs. 2 and 3, and this arm 45 is spring-pressed to carry its longer member inwardly through a lateral slot 54 in said frame 35 so that the end of said member may normally rest in a position in which it may coöperate with the shoulder 46 in arresting a key or check or other token introduced into the slot 41. At the time the frame 35 has performed a complete rotation and the predetermined quantity of gasoline has been discharged from the cylinder 16, the arm 45 is turned outwardly on its pivot 53 to release the key or check 27 and permit the same to descend, and this releasing movement of the arm 45 is imparted to it by the front end of a pin 154 carried by a standard 55 which is integral with the frame 38 hereinbefore referred to. During the rotation of the frame 35 to discharge a predetermined quantity of gasoline or the like, the threaded sleeve 37 connected therewith rotates and effects the traveling movement of the frame 38 in a direction toward the frame 35 and at the conclusion of this movement the front end of the pin 154, engages the short member of the arm 45 and turns said arm to carry its longer member from the key or check 27, thus releasing said key or check to descend. The standard 55 has upon its upper end a plate 56 which projects forwardly and which, during the rotation of the frame 35 to discharge the quantity of the gasoline, travels with the standard 55 and is carried below the entrance slot 26, thus forbidding the entrance of any further key or check to the machine at that time. During the reverse rotation of the disk 29 and frame 35 to restore the slot 41 in said frame to its initial position and effect the movement of the plunger 15 in the cylinder 16 to its initial position, the frame 38 and standard 55 travel rearwardly from the frame 35 and during such movement the pin 154 releases the arm 45 to take its initial position, and the plate 56 is carried from below the slot 26, thus leaving the machine in proper condition for the subsequent operation thereof. The forward end of the pin together with the short member of the arm 45 serves as a stop to arrest the mechanism after a complete rotation in one direction has been per-

formed, and a pin 57 carried by the standard 55 serves, by engaging a solid part of the casing, to arrest the mechanism therein after the frame 35 has performed its complete reverse rotation.

The keys or checks 27 will be designative in character, as by shape or color or bearing some designation, such as a number or other device, and checks bearing varying designations will indicate by such designations the respective individuals or employees to whom they have been or are to be distributed and whose duty it will be to operate the machine and account for the keys or checks intrusted to them. One system of using the machine would be to designate the individual employees by the same numerals as those on the respective keys or checks intrusted to them, each employee receiving a set of checks for his special use and being compelled to account for the checks or for the value represented by them. The checks or keys may not have a standard value, since the liquids to be sold or purchased will vary in value from time to time and also vary in value in respect to, say, gasoline bringing one price and oil a different price.

The invention will be substantially understood from the foregoing description without further detailed explanation. One point of the invention resides in the applicability of the features of my invention to the ordinary shaft 11 of a gasoline dispensing apparatus, thereby avoiding the construction of special apparatus to accompany my invention and rendering my invention more useful to the public in that it may be directly applied to apparatus already in hand. When the shaft 11 is of the proper size to at once receive the casing 10 and frame 35, the sleeve 30 hereinbefore referred to will be omitted, and when the shaft 11 is less in diameter than the bore of the frame 35 a sleeve 30 will be placed thereon to properly increase such diameter of the shaft. When the frame 35 is in its initial position shown in Fig. 2 the key or check 27 will be fed thereto and the disk 29 and said frame 35 given a complete rotation in one direction to effect the discharge of the predetermined quantity of gasoline, and thereupon the key or check having been released to descend through the chute 48, the disk 29 and frame 35 will be given a complete reverse rotation in order to properly set the plunger 15 in the cylinder 16 and cause the plate 56 to recede from below the entrance slot 26 and the pin 154 from the arm 45, the frame 35 becoming arrested in its initial position ready to receive a further key, check or other token.

I desire it to be understood that my invention is not limited to the details of construction hereinbefore described as illustrative of one embodiment thereof. In carrying out

my invention in the form illustrated, I utilize the known container 19, measure or cylinder 16 and plunger 15, said cylinder and plunger constituting what may be termed a 5 single acting pump, but I do not confine my invention to use with any special style of pump so long as the main purposes of the invention are carried into effect.

What I claim as my invention and desire 10 to secure by Letters Patent, is:

1. Apparatus of the character described comprising a shaft, mechanism to be operated therefrom, a crank for the manual operation of said shaft and normally free thereof, and check or key control means interposed between said crank and shaft and comprising a primary member normally free to rotate independently of said shaft and connected with said crank, a second rotary 15 member rigid on said shaft and to be temporarily connected with said primary member by the introduction of a key or check between them so that the motion of one may be communicated to the other and to said 20 shaft, means for supporting said check or key in operative position, means for releasing said check or key after said members and shaft have completed their movement, and means for preventing said members and 25 shaft after starting on their said movement from being reversed in rotation while the check or key is in operative position, and said means comprising a series of inclined spring dogs extending in the path of the 30 check or key and yieldable to the same on its forward travel but not on any attempted reverse movement thereof.

2. Apparatus of the character described comprising a shaft, mechanism to be operated therefrom, a crank for the manual operation of said shaft and normally free thereof, and check or key control means interposed between said crank and shaft and comprising a primary member normally free 40 to rotate independently of said shaft and connected with said crank, a second rotary member rigid on said shaft and to be temporarily connected with said primary member by the introduction of a key or check 45 between them so that the motion of one may be communicated to the other and to said shaft, means for supporting said check or key in operative position, and means for releasing said check or key after said members and shaft have completed their movement, and shaft have completed their movement, said releasing means comprising a threaded 50 sleeve rigid on said shaft, an internally threaded non-rotary frame on said sleeve and a part carried by said frame to engage and move the check supporting means from the check on the completion of said movement of said members.

3. Apparatus of the character described comprising a shaft, mechanism to be operated therefrom, a crank for the manual op-

eration of said shaft and normally free thereof, and check or key control means interposed between said crank and shaft and comprising a primary member normally free to rotate independently of said shaft and 70 connected with said crank, a second rotary member rigid on said shaft and to be temporarily connected with said primary member by the introduction of a key or check between them so that the motion of one may 75 be communicated to the other and to said shaft, means for supporting said check or key in operative position, and means for releasing said check or key after said members and shaft have completed their movement, 80 combined with an inclosing casing for said control means having an entrance slot for the check or key, and means operable by the rotation of one of said members for closing said slot during the operation of the machine 85 and comprising a threaded sleeve rigid with said member, an internally threaded non-rotary frame on said sleeve and a laterally projecting plate carried by said frame to travel into the plane of said slot during the 90 operation of the machine.

4. Apparatus of the character described comprising a shaft, mechanism to be operated therefrom, and a crank for the manual operation of said shaft in both directions 95 and normally free thereof, associated with check or key control means interposed between said crank and shaft and comprising a primary member normally free to rotate independently of said shaft in either direction and connected with said crank, a second rotary member rigid with said shaft and to be temporarily connected with said primary member by the introduction of a check or key between them, means for supporting 100 said check or key in operative position, means for releasing said check or key after said members and shaft have completed their movement in one direction, and means for connecting said members on the reverse motion of said crank for restoring the mechanism to its initial position.

5. Apparatus of the character described comprising a shaft, mechanism to be operated therefrom and a crank for the manual 110 operation of said shaft in both directions and normally free thereof with check or key control means interposed between said crank and shaft and comprising a primary member normally free to rotate independently of said shaft in either direction and connected with said crank, a second rotary member rigid with said shaft and to be temporarily connected with said primary member by the introduction of a check or key between them, 120 means for supporting said check or key in operative position, means for releasing said check or key after said members and shaft have completed their movement in one direction, and means for connecting said mem- 125 130

bers on the reverse motion of said crank for restoring the mechanism to its initial position, one of said members being a disk having a laterally extending arm to engage the 5 check or key, and the other of said members having two lateral walls with a slot between them to snugly receive the check or key and a slot through them in the plane of said arm.

6. Apparatus of the character described 10 comprising a shaft, mechanism to be operated therefrom and a crank for the manual operation of said shaft in both directions and normally free thereof, associated with check or key control means interposed between said crank and shaft and comprising a primary member normally free to rotate independently of said shaft in either direction and connected with said crank, a second rotary member rigid with said shaft and to 15 be temporarily connected with said primary member by the introduction of a check or key between them, means for supporting said check or key in operative position, means for releasing said check or key after said members and shaft have completed their movement in one direction, and means for connecting said members on the reverse motion of said crank for restoring the mechanism to its initial position, combined with an inclosing casing for said control means having an entrance slot for the check or key, and means operable by the rotation of one of said members for closing said slot during the 20 operation of the machine.

7. Apparatus of the character described comprising a shaft, mechanism to be operated therefrom and a crank for the manual operation of said shaft in both directions and normally free thereof, associated with 25 check or key control means interposed between said crank and shaft and comprising a primary member normally free to rotate independently of said shaft in either direction and connected with said crank, a second 30 rotary member rigid with said shaft and to be temporarily connected with said primary member by the introduction of a check or key between them, means for supporting said check or key in operative position, means for releasing said check or key after 35 said members and shaft have completed their movement in one direction, and means for connecting said members on the reverse motion of said crank for restoring the mechanism to its initial position, combined with means for preventing said members and shaft after starting on their forward movement from being reversed in rotation until 40 said forward movement has been completed.

8. Apparatus of the character described comprising a shaft, mechanism to be operated therefrom and a crank for the manual operation of said shaft in both directions and normally free thereof, associated with check or key control means interposed be-

tween said crank and shaft and comprising a primary member normally free to rotate independently of said shaft in either direction and connected with said crank, a second rotary member rigid with said shaft 70 and to be temporarily connected with said primary member by the introduction of a check or key between them, means for supporting said check or key in operative position, means for releasing said check or key after 75 said members and shaft have completed their movement in one direction, and means for connecting said members on the reverse motion of said crank for restoring the mechanism to its initial position, said releasing means comprising a threaded sleeve rigid on said shaft, an internally threaded non-rotary frame on said sleeve and a part carried by said frame to engage and move the check supporting means from 80 the check on the completion of said movement of said members.

9. Apparatus of the character described comprising a shaft, mechanism to be operated therefrom and a crank for the manual 90 operation of said shaft in both directions and normally free thereof, associated with check or key control means interposed between said crank and shaft and comprising a primary member normally free to rotate 95 independently of said shaft in either direction and connected with said crank, a second rotary member rigid with said shaft and to be temporarily connected with said primary member by the introduction of a check or 100 key between them, means for supporting said check or key in operative position, means for releasing said check or key after said members and shaft have completed their movement in one direction, and means 105 for connecting said members on the reverse motion of said crank for restoring the mechanism to its initial position, combined with an inclosing casing for said control means having an entrance slot for the check 110 or key, and means operable by the rotation of one of said members for closing said slot during the operation of the machine and comprising a threaded sleeve rigid with 115 said member, an internally threaded non-rotary frame on said sleeve and a laterally projecting plate carried by said frame to travel into the plane of said slot during the operation of the machine.

10. A shaft, mechanism to be operated 120 therefrom, a crank for the manual operation of said shaft and normally free thereof, check or key control means interposed between said crank and shaft for locking the crank to the shaft on the introduction of a 125 check or key thereto, means for supporting the check or key in operative position, and means for releasing the same after the shaft has made a predetermined movement comprising a threaded sleeve rigid on said 130

shaft, an internally threaded non-rotary frame on said sleeve and a part carried by said frame to engage and move the check supporting means from the check on the completion of said movement of the shaft.

11. A shaft, mechanism to be operated therefrom, a crank for the manual operation of said shaft and normally free thereof, check or key control means interposed between said crank and shaft for locking the crank to the shaft on the introduction of a check or key thereto, means for supporting the check or key in operative position, means for releasing the same after the shaft has made a predetermined movement, an inclosing casing for said control means having an

entrance slot for the check or key, and means for automatically closing said slot during the actuation of said mechanism from the shaft, said slot-closing means comprising a threaded sleeve rigid on said shaft, an internally threaded non-rotary frame on said sleeve and a plate carried by said frame to travel into the plane of said slot during said movement of the shaft. 20

Signed at New York city, in the county of New York and State of New York, this 3rd day of December A. D. 1913. 25

CHARLES S. BATDORF.
